(57) **CLAIM**

The ornamental design for a sensor, as shown and described.

DESCRIPTION

FIG. 1 is a front view of a sensor showing our new design;
FIG. 2 is a left-front perspective view of the sensor;
FIG. 3 is a right-front perspective view of the sensor;
FIG. 4 is a rear view of the sensor;
FIG. 5 is a left-rear perspective view of the sensor;
FIG. 6 is a top view of the sensor;
FIG. 7 is a right-side view of the sensor;
FIG. 8 is a bottom view of the sensor;
FIG. 9 is a left-side view of the sensor;
FIG. 10 is a front view of a sensor according to a second embodiment showing our new design, all other views of the second embodiment are identical to that of the first embodiment but have not shown for ease of illustration;
FIG. 11 is a front view of a sensor according to a third embodiment showing our new design;
FIG. 12 is a front view of a sensor according to a forth embodiment showing our new design;
FIG. 13 is a front view of a sensor according to a fifth embodiment showing our new design; and,
FIG. 14 is a front view of a sensor according to a sixth embodiment showing our new design.
The broken lines are included for purposes of illustrating a portion of the sensor that forms no part of the claimed design.
